UNITED STATES PATENT OFFICE.

LEVI B. MILLER, OF LYNN, MASSACHUSETTS, ASSIGNOR TO GENERAL ELECTRIC COMPANY, A CORPORATION OF NEW YORK.

MACHINE AND PROCESS FOR PREPARING QUARTZ.

Application filed July 18, 1924. Serial No. 726,865.

To all whom it may concern:

Be it known that I, Levi B. Miller, a citizen of the United States, residing at Lynn, in the county of Essex, State of Massachusetts, have invented certain new and useful Improvements in Machines and Processes for Preparing Quartz, of which the following is a specification.

My invention relates to a machine and process for preparing quartz. Heretofore, as far as I am aware, no device has been contrived by means of which quartz, while it is in a hot plastic state may be cut off into rods or canes of suitable length from what for convenience I will term a rope of the material which is squirted or forced from a reservoir in a furnace such as a crucible. Nor has there been contrived a device for conveying off lengths of the cut quartz rods while they are still hot to make room in order that the rope may advance before the cutter in order that another rod or a series of other rods may be cut from the same rope one after another until the material in the crucible is exhausted.

An object of my invention is to provide a device of the above character by means of which hot plastic or molten quartz may be formed into a rope from a single mass within the furnace which may be termed a puddle and cut into suitable lengths during a single heat of the crucible. For the purpose of clearness and convenience, the stream of quartz as it emerges from the furnace may be termed a rope to distinguish it from the rods which are cut therefrom. In a device of the above character the expulsion of the rope from the nozzle of the furnace may become intermittent if the expulsion process at the instant of cutting is momentarily held up.

While the form of apparatus shown in the drawing contemplates the continuous process, nevertheless the operation of producing the rods may be intermittent.

The means for accomplishing the foregoing and other useful ends are hereinafter more fully set forth and claimed, reference being had to the accompanying drawings in which:

Fig. 1 is a perspective view of the fused quartz cane cutting machine, showing the quartz and the machine in the starting position;

Fig. 2 is a plan view of the machine show-

ing the quartz in position just before being clamped;

Fig. 3 is an enlarged fragmentary view showing one of the clamps pivoted above the table and one below, clamping the quartz in position after it is cut or just before;

Fig. 4 is a cross section of the table showing how the clamps are held and locked in position;

Fig. 5 is an enlarged view of the drive and the friction clutch;

Fig. 6 is an end elevation of the machine showing the table in section with the quartz in position before it is clamped and a dotted illustration of it after it is clamped;

Fig. 7 is a rear view of the machine showing especially the starting and stopping mechanism;

Fig. 8 is a section of the table and the shearing mechanism showing the quartz after it has been cut; and

Fig. 9 is an enlarged view of the starting and stopping mechanism showing the position of the stop in full in the locked position and in dotted lines in the unlocked position.

Referring more in detail to the drawings, the furnace A, Fig. 1, where the molten or plastic material is contained, is shown above the receiving device or conveyor B while a cutting device or shears C is shown located in between the two. The furnace is provided with a suitable nozzle 2 through which a rope of plastic quartz from the mass 3 is forced, within which furnace it will be understood the mass is sufficiently heated to render it plastic or molten. In order to force the quartz out through the nozzle there is provided a suitable piston 4 above the quartz. As shown the quartz Q after leaving the nozzle passes between the blades 5 and 6 of the shears C. The receiver or conveyor B below the shears is provided with a number of tongs E set around the circumference of a rotatable plate 7 of the conveyor. The periphery of the plate forms one jaw of each one of the tongs as shown. Each tong is provided with a pivoted jaw such as the jaws 8, Fig. 2, all of which are pivoted to the plate 7 by means of suitable pins p. These pivoted jaws are set alternately, as shown in Fig. 6, of the drawing, on the upper and the lower side of plate 7. However, this arrangement is not essential as they may all very well be located on a single side of the plate. Each movable jaw is provided

85

90

105

110

with a spring such as the spring 9. These springs are so designed and attached to their respective jaws that when the jaw 8, for example, is opened quite wide the end 10 of the spring rests on the flat face of the peripheral zone 11 of the plate 7. Immediately within the zone 11 there is provided a V-shaped groove 12, the outermost side of which slopes inwardly from its rim 13. This groove is so constructed that if the jaw 8 is closed until the end 10 of the spring 9 passes within the outer rim 13 of the groove the tension of the spring and the sloping side of the groove will cause the jaw 8 to be drawn in toward the rim of the plate 7 and to be held quite firmly. The force with which the jaw is thus drawn toward the rim may be well regulated by regulating the tension of the spring 9. This tension is sufficient to hold a rod cut from the plastic rope between the jaw 8 and the face of the plate 7, and prevent its falling as the plate 7 is rotated, as will more fully hereinafter appear.

25 When the rope of quartz Q, which is shown extending out of the nozzle 2, advances a distance below the shears C equal to the length of rod desired the shears are closed thereby cutting off that portion of the rope below the shears. This operation causes one of the tongs on the conveyor B to catch and hold the rod thus cut and it also causes the table 7 to be advanced so as to carry the rod from under the shears substituting a new tong ready for receiving the next rod.

30 The mechanism, by means of which the operations described are carried out, may be described as follows: It will be observed that the blade 6 of the shears C has a coiled spring 14 mounted on an offset element 15, which spring, as the blade 6 closes, engages the jaw 8, as indicated in Fig. 2, thereby presses the jaw 8 against the quartz rope. 45 The result is that the forward end of the spring 9 advances into the groove 12 and the jaw 8 is drawn in with sufficient force against the quartz for holding the rod after it is cut as explained.

50 It will be observed that the plate 7 is provided on its upper side with a crown tooth gear, a tooth 17 of which is adapted to be engaged by a pin 16 mounted above the plate. This pin 16 is connected through the medium 55 of a wire X with the handle of the blade 6 of the shears C. When the blade 6 is closed in the cutting operation the pin 16 is raised through the medium of the wire X with the result that the pin 16 disengages the tooth 17 and the plate 7 rotates and advances the next tong to a position under the cutting edge of the shears C, in which position it is stopped as the pin 16 engages the next crown tooth 18. This engagement between 60 the pin and the next tooth can take place

inasmuch as the cutting operation is of short duration and the pin is released as soon as the shears are opened at the end of the cutting operation, therefore the pin 16 is released in plenty of time to engage the next 70 advancing tooth 18.

The means for rotating the plate, when the shears are operated comprises a suitable motor Y, Fig. 1, which, through the medium of a worm gear 19 drives the gear 20 which latter is mounted on the same shaft with the plate 7. However, the plate is rigidly secured to the shaft while the gear 20 is merely in driving engagement with the shaft through the medium of a suitable friction 75 clutch Z, Fig. 2. The clutch shown comprises a spring plate 22 which presses against the upper side of the hub of the gear forcing the lower hub against a side of the thrust bearing collar fastened to the shaft either directly or with a loose collar interposed between. The tension of the spring 22 may be regulated by a suitable means, as for example by a pair of interlocking nuts 24 and 25 on the end of the shaft 21. With this arrangement, as soon as the tooth 18 strikes the lower end of the pin 16 the plate 7 is brought to a standstill although the gear 20 continues to rotate slipping, on the shaft 21.

80 In this new position obviously the conveyor is ready for the next rod and as soon as the quartz rope has descended a sufficient distance, determined by the length of the rod desired, the shears C are again operated with a repetition of the action and results, already explained in connection with the cutting of the first rod. Therefore, the plate 7 is again advanced one step carrying a new tong to a position over the shears. Therefore, by repeating the operation as many 100 rods may be cut as will fill the machine, that is, as will bring into use all of the tongs on the plate. When the plate is filled the operation may be suspended until the rods are removed. Or if desired, the rods may be 105 removed one at a time as they have advanced such a distance that they have cooled sufficiently to enable them to be removed. This, of course, can be done without interfering with the continued operation of the 110 machine.

115 In order to remove one of the rods all that is necessary to be done is to seize the rod that is to be removed and at the same drawing out the jaw 8. This will, of course, bring the tension spring 9, Fig. 2, out of the groove 12, which will enable the jaw to remain in the position set. In its set position the jaw must, of course, be sufficiently removed from the rim of the plate 7 to allow the quartz 120 rope to pass in between, as already explained.

125 I have found it advantageous to provide, on the upper side of the blade 6 along the cutting edge of the shears, an angle plate 26, Figs. 1 and 2, which is slotted as indicated 130

to enable it to move in a direction across the front of the cutting edge. This plate is provided with a compression spring 27 on its back side tending always to force the plate forward toward the cutting edge of the blade 6. The object of this plate is to avoid the quartz rope from being drawn out of alinement by the blade 6 when the blade is restored to its open position after a cutting operation. When the shears are closed in the act of cutting the quartz presses the plate 26 back against the force of the spring 27 but as soon as the shears begin to open the force of the spring 27 is sufficient to force the end of the quartz from engagement with the top side of the blade 6 thereby leaving the end free and avoiding any danger of the quartz rope being drawn out of alinement. On the opposite blade 5 of the shears and opposite the angle plate 26, I provide a shield plate 28 having a backward slope away from the cutting edge of the blade. The object of this shield is to prevent the quartz rope from engaging the upper surface of the blade 5.

The two blades 6 and 5 are held together, of course, by any suitable swivel pin or screw 29. On the handle side of the blade 5 a stop element 30 with a cushioned head 31 is provided in order to avoid any objectionable jarring effect that might otherwise result upon the performance of the cutting operation. The cushion 31 may be of rubber or any other similar material.

As shown in Fig. 5 the bearing 23 is suitably secured to a frame consisting of an A shaped structure W, Fig. 2, to which the bearing 23 may be directly attached to the cross member 32 of the A shaped frame. The structure as a whole is shown secured to uprights 33, Fig. 2, of any suitable character. The blade 5 of the shears, as indicated, is permanently secured to the forward part of the structure W.

With the arrangement shown and described it will be seen that the seizing device comprising the jaw 8 is operated automatically by the spring 14 when the cutter is operated. That is, each time that the cutter is operated the seizing device 8 which has advanced into operative relation with the cutter is closed by the operation of the cutter without any thought on the part of the operator who is operating the cutter. Likewise it will be seen that the conveyor B is started and stopped automatically without any thought on the part of the operator when the cutter is operated. The starting operation is initiated at the time that a length of quartz is cut. This initiation takes place through the medium of the wire X which raises the pin 16. The automatic stopping takes place after the cutter is opened inasmuch as in opening the cutter the wire X is released and the pin 16 is allowed to engage

the next tooth on the crown wheel such as the tooth 18 for example. As soon as this engagement takes place the conveyor stops with the next seizing device in operative relation to the cutter. Therefore, the operation of the conveyor both as to starting and as to stopping is entirely automatic, both operations being controlled through the medium of the cutter.

While I have shown and described the principles of my invention in connection with certain specific structures it will be understood that in view of the disclosure the invention may be practised with variations or modifications without departing from the spirit thereof or from the scope of the claims appended hereto.

What I claim as new and desire to secure by Letters Patent of the United States is:—

1. In a machine for cutting plastic quartz, a cutter, means for squirting the plastic quartz through an opening into operative relation with respect to the cutter for cutting purposes, means for seizing a length of the plastic quartz before the cutting operation is performed, said cutter adapted for cutting the seized length from the squirted plastic quartz, and means for advancing the cut lengths of quartz beyond the cutter.

2. In a machine for cutting quartz while in a plastic condition, a cutter, means for squirting the plastic quartz through an opening into operative relation with respect to the cutter for cutting purposes, means for seizing a length of the plastic quartz before the cutting operation is performed, said cutter adapted for cutting the seized length from the squirted plastic quartz, and means for advancing the cut lengths of quartz beyond the cutter, and further means for seizing another length of quartz to be cut and advancing the second length cut beyond the cutter.

3. In a machine for cutting lengths of quartz from a mass while the latter is in a plastic state, means for squirting the quartz through a nozzle into a pendant cane, a cutter for cutting lengths from the pendant cane, and a conveyor for receiving the lengths thus cut and removing them from the neighborhood of the cutter.

4. In a machine for cutting lengths from a mass of quartz while the latter is in a plastic state, a cutter, means for squirting the quartz through a nozzle into a pendant cane and into position in proximity of the cutter, said cutter adapted to be operated for cutting lengths from the pendant cane, a conveyor for receiving the lengths thus cut and for removing them from proximity of the cutter as fast as they are cut.

5. In a machine for cutting lengths from a mass of quartz while the latter is in a plastic state, a cutter, means for squirting the quartz through a nozzle into position

in proximity of the cutter, said cutter adapted to be operated for cutting the squirted quartz into lengths, a conveyor having a set of devices each for seizing a length of quartz before the cutter is operated and for removing the lengths thus cut from proximity of the cutter as fast as they are cut.

6. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated, the conveyor having also means for advancing the devices one after another to the cutter preliminary to the seizure of a length of quartz and for withdrawing each device from the cutter after the length seized by the device is cut.

7. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated and for removing the lengths thus cut from proximity of the cutter as fast as they are cut, and means for operating each seizing device to seize a length before such length is cut.

8. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz at the cutter before the cutter is operated and for removing the lengths thus cut from proximity of the cutter as fast as they are cut, and means for operating each seizing device to seize a length before such length is cut, said means being operated through the medium of the cutter.

9. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz at the cutter before the cutter is operated and for removing the lengths thus cut from proximity of the cutter as fast as they are cut, and means on the cutter for operating one of the seizing devices to seize a length of quartz at the time that the cutter is operating.

10. In a machine for cutting plastic quartz, a cutter, means for elongating the quartz and for advancing the elongated quartz into operative relation with respect to the cutter for cutting purposes, means for seizing the elongated quartz before the cutting operation is performed, and for cutting a length therefrom by means of said cutter, means for removing the cut lengths of quartz away from the cutter to make room for a new length, and means for preventing the quartz from which the lengths are cut from remaining in engagement with the cutting device when the cutter is opened after a cutting operation.

11. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated, the conveyor having also means for advancing the devices one after another to the cutter preliminary to the seizure of a length of quartz and for withdrawing each device from the cutter after the length seized by the device is cut, and means for starting the conveyor in operation each time a length of quartz is cut.

12. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated, the conveyor having also means for advancing the devices one after another to the cutter preliminary to the seizure of a length of quartz and for withdrawing each device from the cutter after the length seized by the device is cut, and means for starting the conveyor in operation each time a length of quartz is cut, said means operated through the medium of the cutter.

13. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated, the conveyor having also means for advancing the devices one after another to the cutter preliminary to the seizure of a length of quartz and for withdrawing each device from the cutter with the length thus cut, and means for automatically causing the

seizing device on the conveyor to seize the quartz.

14. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated, the conveyor having also means for advancing the devices one after another before the cutter preliminary to the seizure of a length of quartz and for withdrawing each device from the cutter with the length thus cut, and means for automatically causing the seizing device on the conveyor to seize a length of quartz, and for automatically causing the conveyor to advance the seizing device beyond the cutter.

15. In a machine for cutting the lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated, the conveyor having also means for advancing the devices one after another to the cutter preliminary to the seizure of a length of quartz and for withdrawing each device from the cutter after the length seized by the device is cut, and means for automatically causing the seizing device on the conveyor to seize a length of quartz, and for automatically causing the conveyor to advance the seizing device beyond the cutter, and for automatically stopping the conveyor with the next succeeding seizing device into operative cutting relation with the cutter.

16. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of quartz before the cutter is operated and for removing the lengths thus cut from proximity of the cutter, each seizing device being provided with means for holding the device open before a quartz length is seized.

17. In a machine for cutting lengths from a mass of quartz while the latter is in a plastic state, a cutter, means for squirting the quartz through a nozzle into position in proximity of the cutter, said cutter adapted to be operated for cutting the squirted quartz into lengths, a conveyor having a set of devices each for seizing a length of

quartz before the cutter is operated and for removing the lengths thus cut from proximity of the cutter, each seizing device being provided with means for holding the device open before a quartz length is seized, and also for holding the seizing device closed after the quartz is seized.

18. In a machine for cutting plastic quartz, a cutter, means for squirting the plastic quartz through an opening into operative relation with respect to the cutter for cutting purposes, a conveyor having means comprising a reciprocating element for seizing a length of the plastic quartz before the cutting operation is performed, said cutter adapted for cutting the seized length from the squirted plastic quartz, the conveyor also advancing the cut lengths of quartz beyond the cutter.

19. In a machine for cutting quartz while in a plastic condition, a cutter, means for squirting the plastic quartz through an opening into operative relation with respect to the cutter for cutting purposes, means comprising a reciprocating element for seizing a length of the plastic quartz before the cutting operation is performed, said cutter adapted for cutting the seized length from the squirted plastic quartz, the conveyor also for advancing the cut lengths of quartz away from the cutter, said conveyor having also further means comprising a reciprocating element for seizing another length of quartz to be cut and advancing the second cut length beyond the cutter.

20. The process of cutting quartz while in a plastic state which consists in drawing the quartz into rope form and allowing the rope to hang subject to gravity, seizing a section of the rope and cutting it from the rope and allowing the section so cut to hang subject to gravity for cooling.

21. The process of cutting plastic quartz which consists in drawing the quartz into rope form and allowing it to hang, cutting the rope into sections while hanging and maintaining the cut sections in a hanging position for cooling.

22. The process of preparing quartz while in a hot plastic state which consists in drawing it into a length, cutting the length into sections while hot and allowing the sections to hang subject to gravity.

23. The process of preparing quartz while in a hot plastic state which consists in drawing it into a length, cutting the length into sections while hot and allowing the sections to hang subject to gravity and supporting the one end while cooling.

24. The process of preparing quartz while in a hot plastic state which consists in drawing it into a length, allowing the length to hang, and cutting the length into sections while hanging.

25. In a machine for cutting lengths of

quartz from a mass while the latter is in a plastic state, means for squirting the quartz through a nozzle into a pendant cane, and a cutter for cutting the cane into sections while the cane is being squirted through the nozzle.

26. In a machine for cutting lengths of quartz from a mass while the latter is in a plastic state, means for squirting the quartz through a nozzle into a pendant cane, a cutter for cutting the cane into sections while the cane is being squirted through the nozzle, and means for pushing the cane off from the cutter.
- 15 27. In a machine for cutting lengths of quartz from a mass while the latter is in a plastic state, means for squirting the quartz through a nozzle into a pendant cane, a cutter for cutting the cane into sections while the cane is being squirted through the nozzle, and a conveyor for receiving the

lengths thus cut and for removing them from the neighborhood of the cutter.

28. In a machine for cutting lengths of quartz from a mass while the latter is in a plastic state, means for squirting the quartz through a nozzle into a pendant cane, a cutter for cutting the cane into sections while the cane is being squirted through the nozzle, and mechanical means for pushing the cane off from the cutter.

29. In a machine for cutting lengths of quartz from a mass while the latter is in a plastic state, means for squirting the quartz through a nozzle into a pendant cane, a cutter for cutting the cane into sections while the cane is being squirted through the nozzle, and resilient means for pushing the cane off from the cutter.

In witness whereof, I have hereunto set my hand this 16th day of July, 1924.

LEVI B. MILLER.
